UNITED STATES PATENT OFFICE.

GEORGE E. QUIGGLE, OF FRUITDALE, ALABAMA.

EXTENSION CAR STEPS.

1,143,433.

Specification of Letters Patent.

Patented June 15, 1915.

Application filed March 13, 1915. Serial No. 14,232.

To all whom it may concern:

Be it known that I, GEORGE E. QUIGGLE, a citizen of the United States, residing at Fruitdale, in the county of Washington and State of Alabama, have invented certain new and useful Improvements in Extension Car Steps, of which the following is a specification.

The present improvements relate to extension car steps designed with a view to facilitating ascent and descent from the car platform.

The object of my device is to provide a foldable extension with novel lifting means for the extension sections whereby to retract the device into an inoperative position entirely folded out of the way and beneath the support for the extension steps. It is comprehended also to employ locking means for retaining the movable parts in their extended or folded positions. This and such other objects as may hereinafter appear are attained by the novel construction, combination and arrangement of parts to be hereinafter specifically described and claimed.

Reference will now be had to the accompanying drawings forming a part of this specification, wherein:

Figure 1 is a front elevation of an embodiment of my invention showing the same in extended position. Fig. 2 is a side elevation showing the retracted or closed position of the extension steps in dotted lines. Fig. 3 is a rear elevation. Fig. 4 is a detail view of the guiding means for the step actuating members. Fig. 5 is a perspective view of the lifting lever used with my device. Fig. 6 is a fragmentary sectional view on the plane indicated by the line 6-6 of Fig. 1. Fig. 7 is a detail elevation of a latch member carried by the lifting lever; and Fig. 8 is a perspective view of the locking catch for holding the extension steps when in raised or retracted position.

Throughout the following detail description, and on the several figures of the drawings, similar parts are referred to by like reference characters.

Specifically describing the embodiment of my device the numeral 1 designates the car platform and 2 a fixed step secured thereto, these parts constituting the support for the extension step attachment which forms the subject-matter of this application.

The extension steps of my device comprise

preferably two step members, the upper designated 3 hingedly connected at 4 to the fixed step 2, the lower designated 5 hingedly connected to the upper step section at 6. Each of these step sections 3 and 5 comprise the usual back member and a tread member, designated 3', 3'' and 5', 5'' respectively.

The mechanism employed for operating my device will now be described. Pivotaly mounted upon the back portion of the fixed step 2 at 7 is disposed a lifting lever 8 most distinctly shown in Figs. 3 and 5, said lever being adapted to move in a vertical plane adjacent to the back of the fixed step 2 hereinbefore mentioned. At an intermediate point on the back of the fixed step are secured vertically arranged spaced guide members 9 between which is slidably mounted a guide block 10.

As will be noted by reference to Fig. 4 the guide block is suitably grooved laterally at 10' for interlocking engagement with the guide members 9 and is also provided with a transverse opening 11 through which extends the free end of the lifting lever 8, said block obviously being slidable upon said lever as well as between its guide members upon movement of the lever upwardly or downwardly. Intermediate the lever and the extension sections of this device are a plurality of actuating members which are preferably cables, rods, or the like and designated 12, 12', each of said members being connected at one end to the block 10 and at the other end to the tread member 3' of the upper step section 3. The connections of the members to the tread 3' are arranged in spaced relation in order to facilitate the proper actuation of the step sections and the back element 3' of the upper step section 3 is formed with a plurality of openings 13 through which said actuating members pass.

It will be obvious from the foregoing description that when the extension steps described are in their extended position they will be retracted upon depression of the upper end of the lifting lever 8, the lifting action of the lever causing movement of the slide block 10 upwardly between its guides and actuating the connecting members 12, 12' which retract or draw the step sections into a position shown most clearly in dotted lines in Fig. 2.

In order to support the extension sections, I provide at each side a jointed brace rod

14 connected at its lower end to the tread member 3" of the upper section 3 and at its upper end extending through the back 3' of said section.

5 At 15 is designated a spring which is adapted to cushion the fall of the extension sections into the operative position shown in Figs. 1, 2 and 3 and the brace rods adequately support the upper step section when 10 in such position. To provide for the proper folding of the step sections I arrange certain arms and links at each side of the steps as will now be described. Secured to the back member 3' of the upper step section at 15 each side is an arm 16 extending forwardly and to the outer ends of these arms is pivotally connected the extremities of a bent rod 17, the transverse portion of which passes adjacent the back member 5' of the step section 5 and being disposed in suitable keepers 18 carried by this element. At an intermediate point in the bent extremities of the rod 17, as at 19 are pivotally connected the links 20 each of which connects with 25 a corresponding rigid rearwardly extending arm 21 carried by the tread element 5" of the step section 5.

Bearing the foregoing description in mind, it will be understood that as the actuating members 12 retract the step sections, 30 the arms 16 above mentioned will cause the rod member 17 to move downwardly on the back 5' in the keepers 18 carried thereby and such movement will cause the tread section 5" to be raised through the pressure incidental to the movement of the rod 17 and through the links 20. The lower step section 5 is, therefore, folded and likewise the upper section 3 is caused to be folded 35 by lifting action of the actuating members 12 so that the various elements will assume the dotted line position shown in Fig. 2 of the drawing. In this position, it is designed that step sections will be locked against accidental extension and the locking means provided will now be set forth.

At the outer end of the lifting lever 8 is mounted a rotatable spring actuated locking catch 22 which is formed with a dog 23 adapted when the lever end is in its upper position as shown in Fig. 1 to engage over a lug 24, the mechanism being thus locked with the steps in extended position. For the purpose of releasing the locked engagement the latch 22 is provided with a foot actuated releasing arm 25 extending through an arcuate slot in the back of the fixed step member 2, said slot being designated 26. When it is desired to retract the extension 50 steps the operator places his foot upon the arm 25 disengaging the dog by rotation of said latch about the bar as its axis from the lug 23, a continued pressure enabling the lifting arm to be raised and the block 10 to 55 be similarly elevated, in turn actuating the

members 12, 12' for withdrawal of the extension steps. At a position spaced from the latch 22 at the opposite side of the pivot 7 for the lifting bar 8 a second latch 27 is disposed, this latch corresponding in all details to the latch 22 hereinbefore described. This latch has also a releasing arm as will be understood which extends through an arcuate slot 28 formed in the back of the fixed step 2 and engages over a lug 29 when the lever has been lifted for retraction of the extension steps thereby holding the steps in folded position. In order to most adequately support the steps in folded position just mentioned and to relieve strain upon the lever 8 and its parts I preferably provide as a support an independent latch member 30 at one side of the fixed step 2 with which latch the steps engage as they are brought into the raised position. This latch is most clearly shown in Fig. 8 and has formed thereon a releasing arm 31 which is accessible to the operator in that said arm projects through the back of the the step 2. To release the steps the latch 30 is disengaged whereupon the operator will place his foot upon the releasing arm of the latch member 27 disengaging said latch and the steps will immediately gravitate to their extended position, assisted by actuation through the rod connection 12' which operates in a slot 12" in the step 2.

The foregoing describes a simple method of providing an extension arrangement for car steps and it will be obvious that slight changes may readily be made in the details of the construction without departing from the spirit of the invention and within the scope of the claims hereto appended.

Having thus described my invention, what I claim as new is:

1. An extension car step construction comprising folding step sections adapted to be extended from a car, means for retracting the sections into folded position comprising a lifting lever, actuating means intermediate the step sections and the lever, and guiding means including a movable part operatively connected to the lever and to the actuating means for maintaining operative relation between these parts when actuated.

2. An extension car step construction comprising folding step sections adapted to be extended from a car, means for retracting the sections into folded position comprising a lifting lever, actuating means intermediate the step sections and the lever, and guide means slidably connected to the lever and also having connection with the actuating means, said guide means being movable in a vertical plane by the lifting lever.

3. An extension car step construction comprising folding step sections adapted to be extended from a car, means for retracting the sections into folded position comprising

1. A lifting lever, actuating means intermediate the step sections and the lever, and guiding means establishing operative connection between the lever and the actuating means, 5 said guide means including a block shiftable on the lever during movement of the latter whereby to impart lifting action in a vertical plane to the actuating means.
2. An extension car step construction comprising a pair of step sections, each consisting of a tread and back elements, a lifting lever carried by the car, an actuating member connected with one of the sections aforesaid, guide means to which the guiding member is connected slidably on the lever and having sliding connection with the car, and actuating means intermediate the elements of each section for folding and unfolding of the elements upon actuation of the steps by the lifting lever aforesaid.
3. An extension car step construction comprising in combination with a support, a lifting lever pivoted on the support, a block through which the lever extends shiftable 15 therealong, guide means for the block on the support whereby the block is adapted to move in a vertical plane, foldable step sections connected to the support for extension and retraction, and a plurality of actuating connections intermediate the block and the step sections.
4. An extension car step construction comprising in combination with a support, a lifting lever pivoted on the support, a block 20 through which the lever extends shiftable therealong, guide means for the block on the support whereby the block is adapted to move in a vertical plane, foldable step sections connected to the support for extension and retraction, and a plurality of actuating connections intermediate the block and the step sections.
5. An extension car step construction comprising in combination with a support, a lifting lever pivoted on the support, a block 25 through which the lever extends shiftable therealong, guide means for the block on the support whereby the block is adapted to move in a vertical plane, foldable step sections connected to the support for extension and retraction, and a plurality of actuating connections intermediate the block and the step sections.
6. An extension car step construction comprising in combination, a support, a lifting lever pivotally mounted for movement in a vertical plane adjacent to the support, spaced guide members carried by said support, a slideable guide block operable between the spaced guide members and having an opening therethrough through which the lifting lever extends, foldable step sections hingedly connected together and to the support aforesaid, actuating connections intermediate the step sections and the guide block aforesaid, jointed brace means for cushioning and supporting the step sections when in extended position, and means connected to the step section elements for imparting folding action thereto upon actuation of the lifting lever aforesaid.
7. An extension car step construction comprising folding step sections adapted to be extended from a car, means for retracting
8. An extension car step construction comprising in combination with a support, a lifting lever pivoted on the support, a locking member on said lever for holding the lever in inoperative position, said member including a support engaging dog and a foot actuating arm, foldable step sections connected to the support, and actuating means intermediate the lever and the sections.
9. An extension step construction comprising in combination with a support, a lifting lever pivoted on the support, a spring actuated locking member rotatable on said lever and automatically engageable with the support, said member including a releasing arm for rotating and disengaging the same, foldable step sections connected to the support, and actuating means intermediate the lever and the sections.
10. An extension car step construction comprising in combination a support, a lifting lever pivoted adjacent to one end thereof to said support, locking members carried by said lever in spaced relation and disposed thereon at opposite sides of the pivot to said lever, each locking member having a releasing arm, the said support having slots through which the releasing arm aforesaid extend, foldable step sections hingedly connected to the support, actuating cables connected at one end to the step sections, guide means to which the other end of said cables are connected, said guide means comprising a vertically movable block slidably carried by the lifting lever, and spaced guide members on the support with which said guide block interlockingly engages, and an independent locking means carried by the support for maintaining the step sections, in folded retracted position.

In testimony whereof I affix my signature in presence of two witnesses.
